UNITED STATES PATENT OFFICE.

JOHN H. MAURER, OF BALTIMORE, MARYLAND, ASSIGNOR OF ONE-HALF TO CHARLES M. WINTERNITZ, OF BALTIMORE, MARYLAND.

HEATING-OVEN.

1,111,913.

Specification of Letters Patent. Patented Sept. 29, 1914.

Application filed May 14, 1914. Serial No. 838,549.

To all whom it may concern:

Be it known that I, JOHN H. MAURER, a citizen of the United States, residing at Baltimore, Maryland, have invented certain new and useful Improvements in Heating-Ovens, of which the following is a specification.

This invention relates to new and useful improvements in heating ovens for tools 10 and the like, and is particularly adapted for use by cabinet makers.

An object of the invention is to provide a combined tool heating oven and glue pot heater which may be operated at a minimum 15 expense.

Another object of the invention is to provide a device in which the joints are formed in such a way as to eliminate the use of solder or any similar material.

With these and other objects in view, the invention consists in the novel combination and arrangement of parts which will be fully set forth in the following specification and accompanying drawings, in which,—

Figure 1 is a front view in elevation of a heating oven constructed in accordance with this invention, Fig. 2 is a top plan view of Fig. 1, Fig. 3 is a longitudinal sectional view taken on line 3—3 of Fig. 2, Fig. 4 is 30 a transverse sectional view taken on line 4—4 of Fig. 3, Fig. 5 is an enlarged detail sectional view showing the method of supporting the grid, and Fig. 6 is an enlarged detail sectional view of the end construction.

Referring now to the drawings, by characters of reference, the numeral 1 designates the main body portion of the device, which is constructed of a single sheet of metal and is bent to form a rectangular casing. A suitable slit 2 is cut in the front wall of the casing and communicates at its terminals with the slits 3 as illustrated in Fig. 1. The metal between the slits 2 and 3 is bent inwardly as at 4 to form the shelf 5, which is supported by means of the angle brackets 6 which are riveted or otherwise secured to the front wall and to the shelf. An enlarged aperture 7 is formed in the back wall of the casing and is arranged to be closed by a suitable cover plate which will be more fully hereinafter described. Formed centrally of the top of the rectangular casing is the aperture 8 in which the grid designated generally by the numeral 9, rests. This grid 9 preferably comprises the ring 10, having

formed integral therewith a plurality of arms 11, the outer ends of which are bent beyond the outer periphery of the ring as at 12 to form supports for the grid when the device is in use.

Secured to the back wall of the casing 1 are the guide plates 13, having the bent-back portion 14 which terminates at its free end in the portion 15, which is arranged to form a guide for the cover plate 16, hereinbefore mentioned. This cover plate 16 is provided at its upper edge with the extension 17 which is arranged to form a handle by means of which the plate may be removed when so desired.

A pair of end members 18 having the angular extensions 19 at their free edges are provided, and each of the extensions is bent back upon itself as at 20 to form the slots 21, in which the edges of the rectangular casing 1, is held. A suitable rivet or other securing means 22, is extended through the angular extension and bent-back portion, and is arranged to rigidly hold the end member 18 in place. Extending longitudinally through the box thus formed is the rod 23 having at each end the threaded portion 24, with which the nuts 25 are arranged to coöperate. This rod 23 is arranged to form a longitudinal reinforcement for the box and also to form a support for the tools when the same are resting on the shelf 5 hereinbefore described. Secured centrally of the lateral extremities and extending longitudinally through the box is a suitable supply pipe 26 having at one end the stop cock 27, by means of which the flow of gas into the pipe is controlled. Secured centrally of the pipe 26 is the T-connection 28 having the pipe 29 connected thereto. This pipe 29 carries at its free terminal the gas burner 30 in which the ordinary tip 31 is held. Thus it will be seen that when the stop cock 27 is opened the gas will flow into the pipe 26 and through the tip 31 where it is ignited and the flame will come centrally of the grid 9 hereinbefore described.

A suitable liquid container 32 is provided and has communicating therewith at spaced intervals the burners 33 in which the wicks 34 are held. These wicks 34 extend into the chamber as clearly shown at Fig. 4, and are arranged to absorb the liquid contained therein.

It will be evident from the foregoing that

in use, the glue pot is stood upon the grid 9, and the gas burner 30 ignited thus causing the glue within the glue pot to become heated. When it is desired to heat any tools or similar devices, the wicks 34 are ignited after the chamber 32 is filled with alcohol or similar liquid, so that the tools may be laid upon the shelf and will be further supported by the rod 23 directly over the alcohol flame. 10 Since this flame creates a white light, it will be apparent that the tools thus heated will not become smoked and may be used without in any way injuring the article.

With the use of this invention it will become apparent that it is not necessary to have a separate heating device for the tools and for the glue pot and also that the heat generated from the tool heating burner will materially assist in the heating of the glue 15 pot and consequently considerable saving of fuel will be effected.

While in the foregoing there has been shown and described the preferred embodiment of this invention, it is to be understood 20 that such changes may be made in the combination and arrangement of parts as will fall within the spirit and scope of the invention as defined in the appended claim.

Having thus described my invention, I claim:

A heating oven including a rectangular casing, said rectangular casing being provided with a longitudinal slot in its front wall, the metal from the slot being bent inwardly and forming a shelf, the top wall of the casing being provided with a central circular aperture, a grid supported by the walls of the aperture, a longitudinal reinforcing bar extending through the casing from end to end, said bar cooperating with the shelf in holding tools which are to be heated, a gas burner centrally of the casing and extending into close proximity with the grid, and a pair of spaced alcohol lamps within the casing to form tool heaters, whereby when tools are laid on the shelf and the supporting bar they will be in direct alinement with the flame from the alcohol lamps and become heated.

In testimony whereof I affix my signature in presence of two witnesses.

JOHN H. MAURER.

Witnesses:

WILLIAM J. McCACKAN,
JAMES L. MUSE.
